US0D1098906S

(12) **United States Design Patent** (10) **Patent No.:** **US D1,098,906 S**
(45) **Date of Patent:** **** Oct. 21, 2025**

(54) **NUT**

(71) **Applicant:** **NeuroDerm, Ltd.**, Rehovot (IL)

(72) **Inventors:** **Eran Shor**, Tel Aviv (IL); **Tsabar Mor**, Adi (IL); **Nir Lilach**, Kfar Yehoshua (IL); **Rami Grossfeld**, Haifa (IL); **Yoav Tikochinsky**, Tel Aviv (IL); **Serdar Ozsumer**, Milan (IT)

(73) **Assignee:** **NeuroDerm, Ltd.**, Rehovot (IL)

(**) **Term:** **15 Years**

(21) **Appl. No.:** **29/940,272**

(22) **Filed:** **May 1, 2024**

Related U.S. Application Data

(63) Continuation-in-part of application No. 18/065,373, filed on Dec. 13, 2022, which is a continuation-in-part of application No. 16/685,364, filed on Nov. 15, 2019, now Pat. No. 11,554,210, which is a continuation of application No. 16/351,061, filed on Mar. 12, 2019, now Pat. No. 10,603,430, which is a continuation of application No. 16/027,804, filed on Jul. 5, 2018, now abandoned, application No. 29/940,272 is a continuation-in-part of application No. 29/779,153, filed on Apr. 16, 2021.

(57) **CLAIM**

The ornamental design for the nut as shown and described.

DESCRIPTION

FIG. 1 is a front perspective view of a nut;

FIG. 2 is a front view of the nut;

FIG. 3 is a rear view of the nut;

FIG. 4 is a right side view of the nut;

FIG. 5 is a left side view of the nut;

FIG. 6 is a top view of the nut;

FIG. 7 is a bottom view of the nut; and,

FIG. 8 is a rear perspective view of the nut.

The broken lines shown in the drawings illustrate the environment of the claimed design and form no part thereof.

1 Claim, 7 Drawing Sheets
